UNITED STATES PATENT OFFICE

ROBERT WILHELM VOIGT, OF DRESDEN, GERMANY, ASSIGNOR TO THE FIRM "UNIVERSALLE" CIGARETTENMASCHINEN-FABRIK J. C. MÜLLER & CO., OF DRESDEN, GERMANY

APPARATUS FOR SHAPING AND FILLING CIGARETTE BOXES

Application filed May 21, 1929, Serial No. 364,833, and in Germany March 5, 1928.

Machines are known for shaping and closing boxes having slides or trays and in particular those for filling the slides of the boxes with cigarettes or like articles.

5 In such apparatus it has already been proposed to move towards one another the slide portion or tray and the shell or case into which it is to be pushed. The slide portion has been shaped during its movement 10 and at the same time the cigarettes inserted in it. Moreover the initially flat shell in its movement has been shaped (i. e. opened) so that on meeting with the shaped and filled slide portion it is located in the correct position to receive it.

Also it has already been recognized that the introduction of the shaped and filled slide or tray into the shell or case presents difficulties and it has been proposed to feed 20 the shells at an angle to the direction of movement to the slide portions therefor in such manner that one corner of the folded slide part first enters the shell.

The present invention, however, not only 25 solves the problem of simultaneously filling the slide and bending upwards the side portions but also the problem of introducing the slide into the shaped shell fed in the same direction in the longitudinal direction 30 of the box.

For this purpose, while the cigarettes are being filled into the slide blank, the side walls are raised and later the completed slide is led on to an inclined track inclined towards the 35 feed track of the shell so that it first with its forwardly projecting front edge enters the shell which is held at its opposite end by means which serve to erect (i. e. open) it. The blank brought into the feed track of the 40 cigarettes is held by a U-shaped bridge falling on it which rests on the bottom of the blank and at the same time permits the introduction of the cigarettes and forms with its limbs abutment surfaces for the side walls adapted 45 to be erected by cams or the like. The slide portions after the cigarettes are introduced and the side walls raised are led by the conveying means, while the slide is at the same time completely closed, into a channel in 50 which the slide portions are fed forwards in

the longitudinal side of the box or packet into a channel with an inclined base the cover of which is formed by the lower flight of an endless conveyor band rotating in a suitable direction. The last part of the inclined base of 55 the channel is movably arranged and operated in such manner that the slide part which passes on to this base portion is led in an inclined position to beaks with the shell fed oppositely to it, whereupon the base portion 60 is lowered in such manner that the slide part is combined with the shell lying wholly in the same plane. The initially flat shell is pushed forward over a former which presents to the shell first a knife-like end and gradually 65 expands to the internal cross section of the erected shell, the shell being fed forward by feeding means engaging the outer side thereof and means being provided for preventing the former from being displaced so 70 as to permit the passage of the shell on to the former. The means for preventing the former from being displaced consist of a number of pins disposed in a row and in the longitudinal direction of the former, and movable 75 towards the former, which pins with their ends are adapted to enter recesses in the former and are so operated that they are moved in succession corresponding to the feed 80 of the shell upwards out of and downwards into the recesses in the former.

The invention is illustrated in the accompanying drawings which show one example of apparatus for boxes having slides or trays 85 filled with cigarettes.

Fig. 1 shows the new apparatus in side elevation partly in vertical cross section on the line 1—1 of Fig. 2. Fig. 2 is a plan view of the new apparatus. Fig. 3 shows in cross section on the line 3—3 of Fig. 4 to an enlarged scale the part shown at the left hand side of Fig. 1. Fig. 4 shows in plan also to enlarged scale the portion shown at the lower left hand side of Fig. 2. Both figures refer 90 to the arrangement for introducing the cigarettes and at the same time erecting the side walls of the slide. Fig. 5 shows the central part of Fig. 1 to enlarged scale. Fig. 6 is a plan view thereof. Fig. 7 shows in vertical longitudinal section the part of the appara- 95 100

tus which serves to connect the two parts of the box. Fig. 8 is a plan view. It will be observed that Fig. 7 is a vertical section on the line 5—5 of Fig. 2 to enlarged scale.

Fig. 9 is a vertical longitudinal section also on the line 5—5 of Fig. 2. It should be noted that Fig. 7 shows the left hand part and Fig. 9 the right hand part of the vertical cross section indicated by the line 5—5. Fig. 10 is a plan view of Fig. 9.

Figs. 11a to 11c show the slide parts and the box shells in different stages of production.

The cigarettes z^1 , z^2 are taken from the containers 1 and 2 by drums 3, 4 and delivered to feed bands 5 and 6 which feed them laterally of the track 7, the cigarettes being deposited in two layers on the track 7. For this purpose a strip 8 is provided which is located at the distance of the diameter of a cigarette above the track 7 and runs parallel thereto. The cigarettes z' pass on to the strip 8 from the container 1 and are gripped by a pushing device 9 having two fingers which device is secured to a chain 10 and the upper finger of which is fed over the strip 8 while the other finger moves between the strip 8 and the track 7. The upper finger of the pushing device feeds the cigarettes z' to the end 11 of the strip whereupon they are deposited on the lower layer formed of the cigarettes z^2 . Both layers of cigarettes are now pushed by the fingers of the pushing device and fed to the slide blank or tray blank beneath the U-shaped bridge 12. The pusher 9 is a bifurcated member of the construction shown in the copending application Serial Number 449,822 of Neff filed May 5, 1930. This pusher while swinging around with the chain to which it is attached will longitudinally displace the two layers of cigarettes relative to one another. To restore them to the proper position on the slide blank before the latter can be folded, as will be presently described, an additional pushing means is used. This pushing means comprises a plate 50 capable of swinging in vertical direction and formed with a wing or part 52 adapted to be actuated by suitable means (not shown). After the positioning of the cigarettes onto the slide blank the plate 50 is swung downwardly against the ends of the cigarettes and thereby pushes them back to be in alignment on said slide.

The slide blanks s are arranged in piles in the holder 13. Beneath the holder slides to and fro a pusher 14 having a lug 15. A lever 16 pivoted at 16b to the machine frame is fitted with a roller 16c which tracks a cam disc 17. The lever 16 is controlled by a spring 16a and engages with its forked end 16d and a pin 14a secured to the pusher 14. The pusher is moved to and fro by this means in such manner that on each stroke it withdraws a blank from the holder 13 and pushes it on to the conveyor band 18. As

soon as the slide blank abuts against the stops 17b (Figs. 3 and 4) the U-shaped bridge 12 is lowered thereon. At the same time the charge of cigarettes is pushed beneath the bridge; at the same moment the pushers 19a move upwards and raise the side walls w of the slide blank (Fig. 11a). Preferably, the pushers 19a and the stops 19b are mounted on a common frame 19. This frame is moved from a cam disc 20 by means of a double armed lever 20a and a link 20b so that the stops 19b first stop the slide or tray and hold it and then the pushers 19a as above described move upwards and raise the side walls w . Thereupon the pushers 19a retreat and the stops 19b move downwards and release the slide. At the same time the bridge 12 moves upwards, the fixed stamp 12a pushing the slide out of the bridge. The pushing member 21 of the conveyor band 18 comes against the filled slide and pushes it through the channel 22. This channel is provided with flanks 23 and 24 which raise the flaps k (Fig. 11a) of the slide or tray vertically and bend over the tongue z so that it lies parallel to the bottom of the slide.

When the slide or tray reaches the end of the channel 22 it is moved by a pushing member 25 which is moved by a chain 26 over a track 27 at right angles to the longitudinal direction of the channel 22. This member pushes the slide or tray through a short channel 28, the folding plates 29 folding the flap k of the slide into its horizontal position and bending over its sides t (Fig. 11a) so that the slide is given its finished form. After the slide has passed through the channel 28 it passes on to the steep inclined plane 30 and beneath the lower flight of the conveyor band 31 and is fed in the direction of the arrow a in Fig. 7 towards the shell of the box.

The flat pressed shells or cases h of the boxes are piled in a holder 32. Pushers 33 extend through a slot in the bottom of the holder, these pushers being carried by a chain 34 and carrying with them on their passage beneath the holder 32 a shell and feeding it in the direction of the arrow (Figs. 7 and 9). The wedge-shaped core or former 35 with its knife-like end 36 enters the openings in the shell. Several such shells h are adapted to continuously engage said former 35 at a time, thereby supporting the former 35 in its position at the desired height from the path of the shells h . The former 35 gradually increases in dimensions until it has the full internal width of the shell and a corresponding rectangular cross section. The shell is thus shaped and opened while it is carried over the former 35. The former must be prevented from moving in the longitudinal direction without the means for feeding the shell over the former being prevented from moving. To this end, recesses 37 are provided in which

the pins 38 alternately engage. These pins under the action of springs 39 are pressed with their upper ends against cams 40 which are mounted on the cam shaft 41 and actuate 5 the pins in such manner that the former 35 is always held by at least two pins. During the passage of the shells over the former, each pin is raised in turn until the shell has pushed past beneath it.

10 At the moment when the slide or tray *s* reaches the position shown in Fig. 7 the shell *h* of the box meets it, the upper front edge of the slide being pushed a little into the shell. At this moment the movable part 42 15 of the steep inclined plane 30 is turned about the pivot 43 into the horizontal position while at the same time the pushing member 33 pushes the shell part of the box over the slide. The part 42 is actuated by means of a cam 20 44 and a spring 45.

The completed box is pushed by a pushing member 46 which hangs from a chain 47, on to a conveyor band 48 which runs parallel to the chain 44 but in the opposite direction 25 thereto and delivers the filled boxes from the machine.

Figs. 11a to 11g show the different stages of the boxes. Fig. 11a shows the slide blank as it comes from the holder 13. Figs. 11b and 30 11c show the slide before and after its passage through the flanks 23 and 24. In Fig. 11d the slide is shown in its finished form. Figs. 11e and 11f show the shell in half and in 25 completely erected position. Fig. 11g shows the finished and filled box as it leaves the machine on the band 48.

I claim:

1. Apparatus for shaping and filling a cigarette box formed of a slide and a shell, comprising means for positioning the cigarettes onto a blank, a bridge member adapted to be lowered onto said blank and to form abutments for the sides of said blank, cam members adapted to raise said side walls after 40 the cigarettes are positioned thereon, an inclined track down which the slide is fed and a feed track for the shell contiguous to the lower end of the inclined track for the slide.

2. Apparatus for shaping and filling a cigarette box formed of a slide and a shell, comprising means for inserting the cigarettes in the slide, a U-shaped bridge member adapted to be lowered on the slide and to form with its limbs abutments for the side walls of the 50 slide, cam members cooperating with such bridge member to raise said side walls, conveying means for feeding the filled slide, a guide channel associated with said conveying means, a cover for said guide channel, said cover formed by the lower flight of an endless conveyor band, and a feed track for the shells contiguous to the end of the guide channel for the slides, substantially as and 55 for the purpose set forth.

3. Apparatus for shaping and filling a

cigarette box formed of a slide and a shell, comprising means for inserting the cigarettes in the slide, a bridge member adapted to be lowered on the slide and to form with its limbs abutments for the side walls of the 70 slide, cam members adapted to raise said side walls, conveying means for feeding the filled slide, a guide channel associated with said conveying means, a cover for said guide channel, said cover formed by the lower flight of an endless conveyor band, said channel having a movable inclined base adapted to be lowered and a feed track for the shells contiguous to the movable inclined base of the 75 guide channel for the slides, substantially as 80 and for the purpose set forth.

4. Apparatus for shaping and filling a cigarette box formed of a slide and a shell, comprising means for inserting the cigarettes in the slide, a bridge member adapted to be lowered on the slide and to form with its limbs abutments for the side walls of the slide, cam members adapted to raise said side walls, conveying means for feeding the filled slide, a 85 guide channel associated with said conveying means, a cover for said guide channel, said cover formed by the lower flight of an endless conveyor band, said channel having a movable inclined base adapted to be lowered, a former presenting to the shell first a 90 knife-like end and a gradually expanded portion expanding to the full internal width of the shell, means for feeding the shell over the former, means for preventing the former from being displaced, and a feed track for the shells contiguous to the movable inclined base of the guide channel for the slides, substantially as 95 and for the purpose set forth.

5. Apparatus for shaping and filling a cigarette box formed of a slide and a shell, comprising means for inserting the cigarettes in the slide, a bridge member adapted to be lowered on the slide and to form with its limbs abutments for the side walls of the slide, cam members adapted to raise said side walls, conveying means for feeding the filled slide, a 100 guide channel associated with said conveying means, a cover for said guide channel, said cover formed by the lower flight of an endless conveyor band, said channel having a movable inclined base adapted to be lowered, a former presenting to the shell first a 105 knife-like end and a gradually expanded portion expanding to the full internal width of the shell, means for feeding the shell over the former, means for preventing the former from being displaced, said means comprising 110

recesses on the former and a row of pins adapted to enter said recesses, and a feed track for the shells contiguous to the movable inclined base of the guide channel for the slides, substantially as 115 and for the purpose set forth.

6. In an apparatus for shaping and filling a cigarette box consisting of a slide and shell,

means for passing cigarettes into a blank slide, means for simultaneously folding the flaps of said slide, means for feeding in an oblique manner said slide, means for feeding 5 a collapsed shell toward said slide, means for opening said collapsed shell during its feeding movement, the angle of inclination of the feed of the slide relative to the feed of said shell being such that the latter will first engage 10 the upper part of the front edge of said slide, and means which, after such engagement of the shell with the slide, will cause the latter to change its angular position so that the shell may be shoved over said slide, said 15 means for opening the collapsed shell comprising a former and a number of members of which at least two at a time are adapted to simultaneously engage said former and which are adapted in turn to disengage said former 20 as the shell passes over it.

In testimony whereof I affix my signature.

ROBERT WILHELM VOIGT.
